(57) **CLAIM**

The ornamental design for an eyebrow shaping stamp, as shown and described.

DESCRIPTION

FIG. 1 is a front perspective view of an eyebrow shaping stamp, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a rear elevation view of the eyebrow shaping stamp, shown in a used condition.

The evenly spaced broken lines showing a user in FIG. 8 depict environmental subject matter and form no part of the claimed design.

The remaining evenly spaced broken lines shown in the drawings depict portions of the eyebrow shaping stamp that form no part of the claimed design.

The contour and shade lines in the drawings represent contoured and shaded surfaces of the claimed design and do not illustrate material, surface ornamentation, or surface decoration.
